[57] **CLAIM**

The ornamental design for an ATV utility hauling accessory, as shown and described.

DESCRIPTION

FIG. 1 is a rear perspective view of an ATV utility hauling accessory showing my new design;

FIG. 2 is a front perspective view thereof;

FIG. 3 is a side elevational view thereof;

FIG. 4 is a side elevational view of the present invention shown in a transitional position;

FIG. 5 is a top plan view of FIG. 4;

FIG. 6 is a bottom view of FIG. 4;

FIG. 7 is a rear elevational view of FIG. 4;

FIG. 8 is a front elevational view of FIG. 4;

FIG. 9 is a side elevational view of the present invention shown in a folded position;

FIG. 10 is a rear elevational view of FIG. 10;

FIG. 11 is a front elevational view of FIG. 10;

FIG. 12 is a top plan view of FIG. 10;

FIG. 13 is a front elevational view of FIG. 10;

FIG. 14 is a rear perspective view of the present invention shown in a folded position;

FIG. 15 is a rear perspective view of the present invention shown mounted on a typical vehicle; and,

FIG. 16 is a rear perspective view of the present invention shown in a folded position, mounted on a typical vehicle.

The vehicle, caster wheel and mounting brackets shown in broken lines are illustrative of environmental structure and are not part of the claimed design.
